VALVE MECHANISM FOR ROCK DRILLS

Raymond H. Smickle, Belvidere, N. J., assignor to
Ingersoll-Rand Company, Jersey City, N. J., a
corporation of New Jersey

Application July 21, 1934, Serial No. 736,293

5 Claims. (Cl. 121—18)

This invention relates to rock drills, but more particularly to a valve mechanism for distributing the pressure fluid to the percussive element of a rock drill.

5 The objects of the invention are to obtain a heavy blow of the percussive element against the working implement, to utilize the pressure fluid expansively and, therefore, to reduce to a minimum the power cost of operating the drill.

10 Other objects will be in part obvious and in part pointed out hereinafter.

In the drawing illustrating the invention and in which similar reference numerals refer to similar parts,

15 Figure 1 is a diagrammatic view, in sectional elevation, of a rock drill equipped with valve mechanism constructed in accordance with the practice of the invention and illustrating the valves and the piston in one of their limiting 20 positions, and

Figure 2 is a view similar to Figure 1 showing the valves and the piston in their other extreme positions.

Referring more particularly to the drawing, 20 25 represents the cylinder of a rock drill having a free exhaust port 21 and containing a reciprocatory hammer piston 22 which controls the exhaust port 21 and carries a stem 23 to deliver blows to a working implement 24.

30 The cylinder 20 is shown as having an integral valve chest 25 which is bored to provide a valve chamber 26 comprising an intermediate portion 27 into which pressure fluid is introduced from supply by a passage 28. At the rear end 35 of the portion 27 of the valve chamber are portions 29 and 30 which form continuations of the valve chamber. The portions 29 and 30 are of larger diameter than the portion 27 and of increasing diameter in the order mentioned. The 40 portion 30 constitutes one end of the valve chamber and serves as a pressure chamber 31 which is sealed by a cover 32.

45 Similarly, at the forward end of the portion 27 is a portion 33 of somewhat larger diameter than the portion 27 and at the outer end of the portion 33 is a portion 34 of larger diameter and of which the outermost end serves as a pressure chamber 35. The pressure chamber 35 is normally sealed by a cover plate 36 which is secured to the valve 50 chamber, as is the plate 32, by a bolt 37 carried in this instance by the plate 32 and extending through the valve chamber 26.

55 Preferably the portion 38 of the bolt 37 lying within the portion 27 of the valve chamber is of reduced diameter and the portions 39 and 40 of

the bolt lying forwardly and rearwardly of the portion 38 extend through valves 41 and 42, respectively, and whereby the distribution of pressure fluid to the ends of the piston chamber 43 containing the piston 22 is effected.

5 The valves 41 and 42 each comprise a stem 44 guided by the portions 29 and 33, and heads 45 on the outer ends of the stems which are guided by the portions 34 and 30 of the valve chamber. The inner ends of the valves constitute pressure 10 surfaces 46 which are constantly exposed to pressure fluid in the portion 27 of the valve chamber and cooperate with seating surfaces 47 at the junctures of the portion 27 and the portions 33 and 29 of the valve chamber to alternately close 15 the ends of the portion 27. The outer ends of the valves also constitute pressure surfaces, designated 48, which form inner bounding surfaces for the pressure chambers 31 and 35.

The pressure fluid distributed by the valves 41 20 and 42 passes through inlet passages 49 and 50 which lead from the portions 33 and 29 of the valve chamber at points adjacent the seating surfaces 47 to the front and rear ends, respectively, of the piston chamber 43. Leading from the 25 piston chamber from a point intermediate the exhaust port 21 and the rear end of said chamber is a kicker passage 51 which opens into the portion 30 of the valve chamber and registers, in the open position of the valve 42, with a passage 30 52 in the head 45 and opening into the pressure chamber 31.

Likewise, at a point forwardly of the exhaust 35 port 21 is a kicker passage 53 which opens into the portion 34 of the valve chamber to supply 40 pressure fluid to a passage 54 in the valve 41 and opening into the pressure chamber 35. The passages 52 and 54 open into the peripheries of the heads 45 of the valves intermediate the ends of said heads and the peripheral portions of the 45 heads lying outwardly of the passages 52 and 54 constitute sealing surfaces 55 which overlie the adjacent ends of the kicker passages 53 and 51 in the closed positions of the valves to prevent the escape of pressure fluid from the pressure 50 chambers 31 and 35.

The pressure chambers 35 and 31 are provided with separate exhaust passages. The one leading from the chamber 35 is designated 56 and opens into the piston chamber 43 at a point rearwardly of the exhaust port 21 and preferably in the same transverse plane as the point of communication of the kicker passage 51 with the piston chamber. An exhaust passage 57 is provided for the pressure chamber 31 and opens 55

into the piston chamber 43 forwardly of the exhaust port 21 and, in the preferred construction, in the same transverse plane as the kicker passage 53.

- 5 If desired, means may be provided to maintain a body of actuating fluid of nominal or line pressure in the pressure chambers 35 and 31 in the closed positions of the valves 41 and 42. The means illustrated comprise passages 58 leading 10 from the supply passage 28 to points intermediate the ends of the portions 33 and 29 of the valve chamber and registering, in the closed positions of the valves, with annular grooves 59 in the peripheries of the valve stems 44. Opening into 15 the portions 33 and 29 of the valve chambers and preferably adjacent the passages 58 are passages 60 which lead to the pressure chambers 35 and 31 and are communicated with the passages 58 by the grooves 59.
- 20 In order to prevent cushioning of the valves 41 and 42 during their closing movements the innermost ends of the portions 34 and 30 of the valve chamber are vented to the atmosphere through ports 61 in the valve chest.
- 25 The operation of the device is as follows: With the valves 41 and 42 and the piston 22 in the positions illustrated in Figure 1 pressure fluid passes from the valve chamber through the inlet passage 50 into the rear end of the piston chamber to drive the piston toward the working implement. In this position of the parts the valve 41 is held against its seat 47 by pressure fluid in the chamber 35. This pressure fluid is entrapped in the chamber 35 by the piston 22 30 which will then overlie the exhaust passage 56. The exhaust passage 57 will then be in communication with the atmosphere through the main exhaust passage 21 so that only atmospheric pressure exists in the pressure chamber 31.
- 35 40 The pressure fluid flowing over the pressure surface 46 holds the valve 42 open during the charging of the rear end of the piston chamber 43, and in this position of the valve 42 the passage 52 is in registry with the kicker passage 51.
- 45 As the piston proceeds forwardly it uncovers the passages 51 and 53. Pressure fluid is thus admitted through the kicker passage 51 and the passage 52 into the pressure chamber 31 to shift the valve 42 against its seat 47.
- 50 As the valve 42 proceeds towards its seat the passage 52 moves out of registry with the passage 51 and the sealing surface 55 covers the adjacent end of the kicker passage 51 so that the pressure fluid previously admitted into the pressure chamber 31 is entrapped therein by the sealing surface 55 and the piston 22 which 55 will then overlie the exhaust passage 57.
- 55 After the valve 42 has been shifted against its seat 47 the supply of pressure fluid to the rear 60 end of the piston chamber is cut off. The pressure fluid in the rear end of the piston chamber 43 thereafter acts expansively to drive the piston on its forward course until the rear end of the exhaust port 21 is uncovered by the piston.
- 65 Meanwhile the valve 42 is held closed by the pressure fluid entrapped in the pressure chamber 31 and by pressure fluid flowing through the passages 58, 59, and 60 into the pressure chamber 31. At this point in the cycle of operation the 70 pressure fluid in the rear end of the piston chamber is exhausted to the atmosphere, as is also that contained in the pressure chamber 35. The pressure fluid acting against the pressure surface 46 of the valve 41 then shifts said valve 75 forwardly to open the inlet passage 49.

In the new position of the valve 41 its groove 59 is out of registry with the adjacent passage 58 so that the flow of pressure fluid from supply to the pressure chamber 35 will be cut off and the pressure chamber is opened to the atmosphere through the exhaust passage 56, the rear end of the piston chamber and the main exhaust port 21 and the passage 54 will be in registry with the kicker passage 53. The pressure fluid in the front end of the piston chamber will then 10 actuate the piston 22 rearwardly.

When the piston uncovers the kicker passage 53 pressure fluid passes into the chamber 35 and the valve 41 is moved thereby to its seat 46, thus communicating the passages 58 and 60 through 15 the groove 59 to assure full line pressure in the pressure chamber 35. Both valves will then remain closed until the front edge of the exhaust port 21 is uncovered by the piston 22 to permit the exhaust of pressure fluid from the front end 20 of the piston chamber to the atmosphere. At the same time the pressure fluid entrapped in the pressure chamber 31 is exhausted and the pressure fluid acting against the actuating surface 46 of the valve 42 will again shift said 25 valve to admit pressure fluid into the rear end of the piston chamber.

In practice, the present invention has been found to be a highly efficient device for effecting the distribution of pressure fluid in rock drills 30 of the hammer type. Owing to the arrangement of the various ports and passages and the manner in which they are controlled by the piston and the valves the pressure fluid is used expansively for actuating the piston through a considerable portion of its stroke. The pressure fluid supply to the piston chamber may be cut off at any suitable or desired point in the stroke of the piston and before the main exhaust port 21 is uncovered. In consequence, an efficient drilling 40 action may be obtained with a minimum consumption of pressure fluid since, as may be readily observed, no pressure fluid is exhausted to the atmosphere without first performing useful work.

I claim:

1. In a fluid actuated rock drill, the combination of a cylinder and a piston, an exhaust port in the cylinder controlled by the piston, a valve chamber, inlet passages leading from the valve chamber to the ends of the cylinder, valves in the valve chamber for controlling the inlet passages and having actuating surfaces, said valves having portions constantly exposed to pressure fluid for actuating them in one direction, passages for conveying pressure fluid from the cylinder to the actuating surfaces to actuate the valves in the opposite direction, means for entrapping such pressure fluid in the valve chamber, and exhaust passages for conveying the entrapped pressure fluid from the valve chambers to the cylinder and being controlled by the piston.

2. In a fluid actuated rock drill, the combination of a cylinder and a piston, an exhaust port in the cylinder controlled by the piston, a valve chamber, inlet passages leading from the valve chamber to the ends of the cylinder, valves in the valve chamber for controlling the inlet passages, said valves being constantly exposed at one end to pressure fluid for actuating them in one direction, kicker passages for conveying pressure fluid from the cylinder to the valve chamber and being controlled by the piston and the valves, passages in the valves to register with the kicker passages for supplying pressure fluid to the ends of the valve chamber for actuating

the valves in the opposite direction, and exhaust passages for conveying pressure fluid from the ends of the valve chamber to the cylinder and being controlled by the piston.

- 5 3. In a fluid actuated rock drill, the combination of a cylinder and a piston, an exhaust port in the cylinder controlled by the piston, a valve chamber, inlet passages leading from the valve chamber to the ends of the cylinder, valves in 5
10 the valve chamber for controlling the inlet passages, differential actuating surfaces on the valves of which the surfaces of smaller area are constantly exposed to pressure fluid for actuating the valves in one direction, kicker passages for 10
15 supplying pressure fluid from the cylinder to the actuating surfaces of larger area for throwing the valves in the opposite direction and being controlled by the piston and the valves, and exhaust passages for conveying the pressure fluid from 15
20 the actuating surfaces of larger area to the cylinder and being controlled by the piston.

4. In a fluid actuated rock drill, the combination of a cylinder and a piston, an exhaust port in the cylinder controlled by the piston, a valve chamber, inlet passages leading from the valve chamber to the ends of the cylinder, valves in the valve chamber for controlling the inlet passages, differential actuating surfaces on the valves of which the surfaces of smaller area are 20
25 constantly exposed to pressure fluid for actuating the valves in one direction, kicker passages for supplying pressure fluid from the cylinder to 25
30

the actuating surfaces of larger area for throwing the valves in the opposite direction and being controlled by the piston and the valves, passages for conveying pressure fluid from supply to the actuating surfaces of a larger area for holding the valves in a limiting position and being controlled by the valves, and exhaust passages for conveying the pressure fluid from the larger actuating surfaces to the cylinder and being controlled by the piston. 10

5. In a fluid actuated rock drill, the combination of a cylinder and a piston, an exhaust port in the cylinder controlled by the piston, a valve chamber, front and rear inlet passages leading from the valve chamber to the corresponding ends of the cylinder, valves in the valve chamber to control the inlet passages and having differential pressure surfaces of which the surfaces of smaller area are constantly exposed to pressure fluid for shifting the valves to open 20
25 the inlet passages, kicker passages leading from points forwardly and rearwardly of the exhaust port to corresponding points in the valve chamber to supply pressure fluid to the actuating surfaces of larger area for actuating the valves to 25 and holding them in closed positions, said kicker passages being controlled by the piston and the valves, and crossed exhaust passages for conveying the holding pressure fluid to the cylinder and being controlled by the piston. 30

RAYMOND H. SMICKLE.
